DOOR HOLDER

Edward H. Wingate, Jr., Birmingham, Ala.

Application November 7, 1949, Serial No. 126,011

2 Claims. (Cl. 292—338)

1. My present invention relates to door holders and has for an object the provision of a device of the character designated which shall be simple and economical of construction, positive of operation, and which shall automatically remain in inoperative position when the floor engaging member thereof is manually raised to inoperative position.

Another object is to provide a door holder embodying a body member adapted to be attached to the door, together with a U-shaped floor engaging prop member formed of resilient material having its legs pivoted to the legs of the U-shaped body and engageable with sloping portions provided on opposed ends of the body, whereby the prop is spring biased into engagement with the floor to hold a door open, and to accomplish this result with a complete unit made of only two parts.

Another object is to provide the body with other sloping portions disposed to be contacted by the prop whereby when the prop is raised slightly above horizontal position it snaps upwardly to inoperative position, clear of the floor.

A further object is to provide a door holder of the character designated in which the body member is secured to the door and the floor engaging prop comprises a U-shaped member, the body being preferably formed of a plate of steel bent to U-shape and the floor engaging prop being preferably formed of a round steel rod, together with means to pivotally mount the ends of the prop to the outstanding legs of the U-shaped body, whereby the prop legs contact outward sloping ends provided on the legs of the body, thus to be spring biased toward the floor by the inherent resiliency of the material from which the prop is formed when the prop is brought to a position out of parallel to the base of the U-shaped body.

A door holder illustrating the features of my invention is shown in the accompanying drawing forming a part of this application in which:

Fig. 1 is a side elevational view of my improved device attached to a door and showing the same in full lines in door holding position and in dotted lines in inoperative position;

Fig. 2 is a front elevational view of the device;

Fig. 3 is a detail sectional view taken generally along line III—III of Fig. 2; and,

Fig. 4 is a developed plan view of the body portion.

Referring now to the drawing for a better understanding of my invention my improved door holder comprises generally a U-shaped body

member 10 disposed to be secured to the door 11, and a U-shaped floor engaging prop 12 pivotally mounted to the body. As best shown in the developed view, Fig. 4, the body member 10 comprises a sheet of metal, preferably a relatively stiff steel sheet of about 18 gauge. In forming the body I make the ends of the plate triangular as viewed in plan with the apexes 15 substantially coincident with the longitudinal center line of the plate. Along the lines 13 and 14 at each end of the plate 10 I bend the metal to form round bottom groove 16. As best shown in Fig. 3, the centrally disposed triangular ends extend outwardly and forwardly of the body, and are joined tangentially to the curved bottom of the grooves 16. At the longitudinal center of the depressions 16, just inwardly of the apexes of the triangular ends, I provide holes 17. The holes are provided at points on the sheet to lie substantially in the bottoms of the grooves 16 when the latter are formed. The sheet is bent along the lines 18 to provide a base section 19 and legs 21 outstanding therefrom. In the base 19 I provide a pair of holes 22 through which are passed screws 23 for securing the base to the door 11.

The prop member 12 preferably is in the form of a U-shaped rod having a floor engaging base section 24 and legs 26. The diameter of the rod forming the prop is preferably slightly less than the diameter of the grooves 16. On the ends of the legs I provide inwardly bent portions 27 which are disposed to enter the holes 17, thus to pivotally mount the prop to the body 10. The base 24 of the prop may be slightly outwardly bowed as shown in Fig. 2 whereby substantially a point contact with the floor may be obtained.

From the foregoing the method of constructing and using my improved door holder may now be readily explained and understood. With the parts assembled in the manner shown in the drawings I fasten the device to the bottom of the door at such elevation that the prop 12 engages the floor 28 when pivoted out of the bottom of the grooves 16, as clearly shown in full lines, Fig. 1. In this position it will be apparent that the ends of the legs 26 of the member 12 slidably engage the outwardly triangular ends of the legs of the body. Since the body 10 is formed of relatively stiff sheet metal the legs 26 thereof remain substantially normal to the base 19 as shown in Fig. 3. Consequently, when the member 12 occupies the position shown in full lines, Fig. 1, the legs 26 thereof spread outwardly of each other under spring tension due to engagement with the slop-

ing ends of the body legs. The base of member 12 is thus held resiliently against the floor, assuring that the prop holds against the floor. When it is desired to move the prop member 12 to inoperative position the same may be raised with the foot or hand to the dotted line position shown in Fig. 1. It will be apparent that if the U-shaped stop 12 is brought slightly past the apexes 15 of the triangular ends, the tension due to spreading of the prop legs causes the same to slide upwardly, thus causing the prop to assume the vertical dotted line position shown in Fig. 1. In fact, I prefer to make the apexes 15 very sharp so that there will be no dead center position of the member 12, the same either being in the vertical position or bearing at its lower end against the floor.

From the foregoing it will be apparent that I have devised an improved door holder which is simple and economical of manufacture and which embodies a minimum number of working parts. It will also be apparent that by forming the holder of two U-shaped members assembled as shown, the spring tension desired for causing the member 12 to remain resiliently against the floor may be supplied in part by both spring tension of the legs 21 of body member 10 and by spring tension exerted by the legs 26 of the prop 12 flexing about the point of juncture with the base 24 thereof, or, if desired, the prop may be made of rigid, non-resilient material and the body made of spring steel stock. In this case all of the spring tension necessary to proper functioning of the device would be provided by flexing the legs of the body. Likewise, while I have described my invention as being preferably made of metallic members, it will be apparent to those skilled in the art that there may be other materials, such for instance as certain plastics, which are suitable for its manufacture. The claims are therefore intended to cover such materials unless the same are by their terms specifically limited to metallic materials.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a door holder, a U-shaped body formed of a sheet of spring steel to provide a base section

and legs outstanding therefrom, an elongated rounded vertical groove formed in the end of each leg parallel to the base and extending across the leg, the outer end of each leg extending forwardly and outwardly to a point from the outer ends of the rounded groove as viewed in transverse section, said outer ends being triangular as the sheet is viewed in developed plan with the apexes of the triangles coincident with the longitudinal center line of the sheet, there being holes through the legs at the points of intersection of the longitudinal center line of the legs and the bottoms of the grooves, a U-shaped floor engaging prop formed of a rod of spring steel of a diameter to lie in said grooves, and inturned ends on the legs of the prop passing loosely through said openings whereby the sides of the legs of the prop engage the triangular ends of the body when the prop legs are moved out of parallel with the grooves and act to urge the legs to a position where they lie in said grooves.

2. In a door holder, a body of sheet metal having a base section and a pair of oppositely disposed legs outstanding therefrom in planes substantially parallel to each other, means to secure the base of the body to a door, portions on the ends of the legs sloping reversely from an outstanding point on the longitudinal center line of the legs, each leg having a vertical groove formed therein immediately adjacent the outer end thereof and extending across the leg, there being openings in said legs at the longitudinal center of the grooves, a U-shaped resilient floor engaging prop member having inturned members adjacent the ends of the legs thereof passing through said openings, the legs of said prop member being of a shape to fit in said grooves when they are moved to a position parallel to said grooves and being disposed to engage the sloping ends of the legs of the body when the legs of the prop member are pivoted out of parallel alignment with the grooves.
